United States Patent Office

Des. 224,854
Patented Oct. 3, 1972

224,854

TELEVISION STAND OR SIMILAR ARTICLE

Melvin K. H. Choy, 45-219 Nakuluai St.,
Kaneohe, Hawaii

Filed Nov. 17, 1970, Ser. No. 26,036

Term of patent 14 years

Int. Cl. D6—99

U.S. Cl. D6—20

FIG. 1 is a perspective view of a television stand or similar article showing my new design;

FIG. 2 is a front elevational view; and

FIG. 3 is a side elevational view.

I claim:

The ornamental design for a television stand or similar article, as shown.
